SHOE PRESS

William C. Card, Jr., Winthrop, Mass., assignor
to Compo Shoe Machinery Corporation, New
York, N. Y., a corporation of Delaware

Application June 27, 1933, Serial No. 677,809

8 Claims. (Cl. 12—33)

This invention relates to presses for use in the manufacture of shoes and more particularly to presses which are utilized in affixing outer soles to lasted uppers by means of an adhesive cement.

5 A general object of the invention is to provide an improved form of press in which the shoe may be clamped with a minimum expenditure of time and effort on the part of the operator and which is adapted securely to hold in position and apply pressure to lasted shoes of varied sizes.

More particularly, objects of the invention are to provide a shoe press having an inflatable pressure applying pad and supporting means located thereover for holding a shoe in clamped position 15 against the pad, wherein the supporting means is adapted to be kept in a fixed position during the loading and pressing operations so that pressure is applied to the shoe sole by inflation alone, and wherein the shoe supporting means is capable of 20 having its position varied with respect to that of the inflatable pad to compensate for extreme variations in the last dimensions employed, even, for example, such as those encountered when handling adults', children's and babies' shoes on 25 the same press.

Further objects of the invention are to provide a press possessing the above and other advantageous features which is simple and sturdy in construction and efficient in operation.

30 Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had 40 to the following detailed description taken in connection with the accompanying drawings, in which:

Fig. 1 is a side elevation of a shoe press embodying features of the present invention;

45 Fig. 2 is a vertical longitudinal sectional view taken substantially medially through the heel post portion of the press and substantially along line 2—2 of Fig. 3;

Fig. 3 is a vertical transverse sectional view 50 taken along line 3—3 of Fig. 1;

Fig. 4 is a side elevation of another form of shoe press embodying features of the present invention;

Fig. 5 is a vertical transverse sectional view 55 taken substantially along line 5—5 of Fig. 4;

Fig. 6 is a perspective view of a housing member used in the modification shown in Fig. 4; and

Fig. 7 is a vertical transverse sectional view taken substantially along the line 7—7 of Fig. 4.

In my copending application Serial No. 522,738, 5 there is described and claimed an improved form of press adapted to be used for cement-affixing outer soles to uppers. The preferred form of press there shown comprises a base member containing an inflatable pad and having a rigid bow 10 member extending thereover and preferably cast integrally therewith. This bow member fixedly carries toe and heel posts which are adapted to bear on the upper part of a lasted shoe. The inflatable pad there used is of special design and is 15 capable of unusual vertical displacement. When operating such a press, variations in employed last sizes are compensated for by inflation alone, there being no opening and closing or other positional adjustment of the toe and heel post, such 20 as was characteristic of the presses theretofore used.

The presently described press preserves these 25 advantageous characteristics as to quick and easy loading and operating, but instead of having the toe and heel posts located in permanently fixed vertical positions, has one or both thereof located in what may be termed a semi-permanent position, with provision being made for altering this 30 position when desired. Provision of this last feature is especially desirable in factory installations wherein the same press is used in handling shoes having extremely varied dimensional ranges, as when both babies' and adults' shoes are manufactured. With the present form of press, ordinary dimensional variations encountered with 35 a given type of shoe may be compensated for by inflation of the pad alone, without adjustment of the supporting means located above the pad, but when a series of shoes of an entirely different type 40 and dimension are to be subjected to sole affixing operations, the shoe supporting means is given a new vertical location with respect to the pad.

Referring more particularly to the drawings, there is shown in Fig. 1 a press comprising a base 45 10, provided with a pad accommodating cavity 11 and with a rigid bow member 12 which preferably, though not necessarily, is cast integrally therewith. This bow member extends longitudinally over the base and carries a suitably located toe post 13 which, in the embodiment here shown, is preferably cast integrally with bow member 12. Toe post 13 carries at its lower end an instep pad 14 which may be formed of yieldable rubber or the like. Also mounted on bow 50 55

member 12 is a heel post 15 terminating at its lower end in an elongate last engaging seat 16 which is adapted to bear upon the top heel portion of any one of a number of interchangeable lasts. During a given loading and pressing operation the toe and heel posts are adapted to be kept fixed above the base 10, and pressure is applied to the shoe sole through inflation alone. To this end, there is preferably located in pad cavity 11 an inflatable pad 17 which preferably possesses the characteristic features of the vertically expansible inflatable pad described in the above mentioned copending application Serial No. 522,738.

15 Such a pad comprises an inflatable rubber bladder (not shown) having its interior in communication with a combined air inlet and outlet passage 18 equipped at its outer end with a valve 19 which is adapted to be used for both inflating and deflating purposes. The inflatable bladder is confined in a suitable casing, such as leather, and this casing preferably has a pronouncedly full or baggy upper diaphragm. This fullness is accentuated at the middle portion of the pad opposite the shank portion of the shoe, and the casing also preferably has side walls or gussets having an increased height at this middle portion, all as more particularly described and claimed in application Serial No. 522,738. For the purposes 20 of the present invention, it will be understood that there is provided a pad which is capable of sufficient vertical displacement properly to care for variations in employed last sizes so long as this variation is not of an excessive order.

25 Returning now to the heel post 15, there is provided means for locating such post in one of several vertical positions. To this end, the post is slideable in a vertical bore 20 passing through an enlargement 21 cast in the web portion of bow member 12. A pin 22 is passed transversely through post 15 below the bow member 12, and is freely rotatable in the post. Fixedly keyed to this pin for rotation therewith are a pair of identical cams or filler blocks 23 and 24. These 30 are mounted on opposite sides of post 15 and each has a plurality of corresponding abutment faces 25, 26, 27, and 28. Each of these faces is located a different perpendicular distance from the axis of pin 22, and each is adapted to be successively seated in abutting contact against corresponding seat portions 29 on the under side of the bow member enlargement 21. It will be seen that the vertical position of pivot pin 22 and, consequently, of heel post 15 depends upon positioning of one or the other sets of cam faces against abutment 29. Thus, if in Fig. 1 where the cam 23 is shown as having its face 25 abutting the under side of the bow member, the cam were given a quarter turn in a clockwise direction so that cam face 28 were positioned against seat 29, it will be seen that the position of post 15 will be considerably lowered. Intermediate positions between these two extreme vertical positions are obtained through proper positioning of the remaining cam faces 26 and 27. In order conveniently to rotate pin 22 and its associated cams, a handle or lever 30 is screwed into an enlarged head on one end of such pin. Twisting movement of post 15 about its own axis is prevented by the means of a downwardly extending rib 31 on the under side of bow member 12. This rib is snugly embraced by the opposed cams at all times.

70 The upper end of post 15 has detachably screwed thereto an enlarged head 32, between

which and the bow member is located a compression spring 33, which tends normally to urge the heel post 15 in an upward direction and serves to maintain cams 23 and 24 constantly in contact with their cooperating abutments 29. This head 32 and spring 33 are preferably located in a recess 34 which extends downwardly into enlargement 21.

In operation, assuming the cams to be located as illustrated in Fig. 1, a lasted upper and an outer sole are assembled with adhesive therebetween, and placed beneath toe pad 14 and heel seat member 16, the pad being at this time deflated. The pad is then inflated, this inflation serving to expand the pad vertically sufficiently to take up any space between the diaphragm and the shoe or between the shoe and its upper supporting means and to press the sole firmly against the lasted upper while pressing the entire shoe assembly securely against its supporting toe and heel posts. Various sizes of adults' shoes may conveniently be loaded and reloaded with the press set in this manner. When it is desired to handle lasts of markedly smaller sizes, the press while in unloaded condition is adjusted by giving the handle 30 one or more quarter turns so as properly to accommodate the vertical position of heel seat 16 to the smaller sized lasts.

In Fig. 4 there is shown another form of press, wherein the heel post is vertically movable as in the preceding embodiment, and where, in addition, the toe post is movable longitudinally of the bow member better to accommodate extremely small lasts. The press as illustrated in this figure comprises a base 110, having a pad cavity 111 in which is located a pad 117 which preferably is similar in construction to that used in the previously described embodiment. A longitudinal bow member 112 is fixedly and preferably integrally carried over base 110. Near the forward end of the bow member is fastened a toe post 113 having a rubber instep pad 114 affixed to its lower end. At the front the bow member 112 is shown to be of an I-beam cross section, including a lower horizontal web 35. The upper end of toe post 113 is provided with a groove 36 having overhanging flanges 37 which overlie web 35 and, together with groove 36, form a slide dovetail connection with web 35. One or both of flanges 37 may be detachable for assembly purposes, as illustrated. A set screw 38 serves to keep the toe post locked in any desired position longitudinally of the bow member.

The heel post 115 carries a flat elongate last contacting heel seat 116, and is of bifurcated construction, comprising two upstanding forks 39 and 40 (Fig. 5). This post is vertically slideable in a three-sided housing 41, which is adapted to be screwed into position on the under side of web 35 and in front of an enlarged portion 46 of the bow member casting. Post 115 fits snugly within the side walls of housing 41 and between the front wall 42 of this housing and the front face 43 of enlargement 46.

The vertical position of heel post 115 is controlled by means of a cam or filler block 123 which is positioned between the forks 39 and 40 and is keyed by means of a set screw to a transverse pivot pin 122 which is freely rotatable in suitable registered openings in the upper ends 70 of forks 39 and 40. The cam is located between these forks as illustrated, and is provided with a plurality of cam faces 125, 126, 127 and 128, which are located at different perpendicular distances from pivot pin 122 and which are adapted 75

successively to be brought into abutting seating contact against the under faces of bow member web 35. The total distance between any two opposed cam faces, such as 125 and 127, is equal to 5 the total distance between the opposed cam faces 126 and 128, and corresponds to the distance between the cam contacting abutment 129 and the lower edge of housing 41, and also to the horizontal distance between the forward face of wall 10 43 and the rearward face of wall 42. The cam and its associated post 115 are thus adapted to be snugly fitted into housing 41 with the cam in any one of several positions. A retaining strap 15 44 is adapted to be screwed in place beneath housing 41 and below cam 123, to prevent the latter from dropping by gravity when the press is in unloaded condition, and to hold the cam snugly in place within the housing. The cam may be 20 adjusted to a new position in order to vary the vertical height of post 115, either by removing this retaining strap and removing and re-inserting the post and cam assembly in housing 41, or by removing the entire housing and its appurtenant parts as a unit and re-attaching it to 25 the press frame after altering the cam position. Since this adjustment need not be made for each press loading operation, but only at infrequent intervals when it is desired to handle an entirely different type of shoe, no undue inconvenience 30 attends upon alteration of the cam position, the location of the heel post being of a semi-permanent nature. In order to facilitate control of the cam while it is having its position adjusted in the housing, an outer end of pivot pin 122 is 35 provided with a handle 130, and the sides of housing 41 are suitably slotted or coped as at 45 to accommodate the transverse pivot pin in any of its several positions.

In operation of this form of press, when lasts 40 of larger sizes are being handled, the heel seat 116 will assume its uppermost position, and toe post 113 will be locked in its foremost position as illustrated in dotted lines in Fig. 5. With these 45 parts thus fixed in position on the shoe press frame, the press may be repeatedly loaded and unloaded in the manner described in connection with the first modification. When an extremely small shoe, such as the baby shoe indicated in full lines in Fig. 5, is to be handled, the toe post 113 and heel seat 116 are shifted to the full line 50 position shown in Fig. 5, and the press may thereafter be successively loaded with shoes of this smaller type, clamping of the shoe being cared for by inflation alone. The best results will be 55 attained by confining the design of this press to babies' and children's shoes, with a maximum capacity for shoes of about the equivalent of size 2½ in the women's range. However, it will be understood that the particular dimensions of 60 any press embodying the herein disclosed structural features are optional, and the appended claims are intended to cover any suitable size range, wherever the context permits.

The first described form of press shown in Fig. 65 1 is primarily intended for operations on lasts of a given category, say women's lasts exclusively. To this end the toe post may be immovable, as illustrated, and the contour of cams 23 and 24 is preferably such as to care for material 70 differences encountered among various women's lasts. However, it will be understood that this form of press (Fig. 1) may, if desired, be equipped with a movable toe post such as that shown in the press of Fig. 4, and/or the cams thereof may 75 be designed to cover a more extensive range,

so that babies', children's and misses' sizes may be handled as well as adults'.

It will be seen that there has been provided a structure which is admirably suited to fulfill the intended functions.

From the above description it will be understood that certain features of the present invention may be utilized in connection with various types of presses used in the manufacture and repair of footwear. Therefore, while for reasons 10 of convenience the illustrated embodiments of the invention have been confined to preferred types of sole-affixing processes, it is to be understood that the invention is not limited to these types or to use in sole-affixing operations as distinguished from sole-laying or sole-leveling operations. Since certain changes may be made in the above construction and different embodiments of the invention could be made without departing from the scope thereof, it is intended 15 that all matter contained in the above description or shown in the accompanying drawings shall be interpreted as illustrative and not in a limiting sense.

It is also to be understood that the following 20 claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A shoe press comprising a base member having an inflatable pad, and supporting means for bearing on the upward face of a lasted shoe assembly, said supporting means including an abutment immovably located over said base, a heel post vertically movable with respect to said abutment, and a cam movably carried by said post and adapted to seat against said abutment, said cam being movable to plurality of positions to determine the height of said post with respect to said abutment.

2. A shoe press comprising a base member having an inflatable pad and shoe supporting means located thereover, said means including an abutment immovably positioned over said base, a heel post vertically movable with respect to said abutment, and means for adjusting the height of said post comprising a rotatable cam interposed between said abutment and post.

3. A shoe press comprising a base member having an inflatable pad and shoe supporting means located thereover, said means including an abutment immovably positioned over said base, a heel post vertically movable with respect to said abutment, a pin carried by said post, a cam mounted on said pin and rotatable about the axis thereof, said cam having a plurality of faces located at different distances from said pin, and means for rotating said cam to present any one of said faces in abutting relation with said abutment.

4. A shoe press comprising a base member having an inflatable pad, a rigid bow member affixed to said base, and shoe supporting means including a heel post vertically movable with respect to said bow member, a pin carried by said post, and a cam rotatably mounted on said pin and having a plurality of faces adapted selectively to abut said bow member to control the height of said post with respect thereto.

5. A shoe press comprising a base member having an inflatable pad, a rigid bow member affixed to said base, and shoe supporting means including a toe post and a heel post independently car-

ried by the said bow member, said heel post being vertically movable with respect to said bow member, spring means urging said post upwardly, and a filler block interposed between said post and said bow member to limit upward movement of the post, the vertical position of said post being determined by the effective thickness of said block.

6. A shoe press comprising a base member having an inflatable pad, a rigid bow member affixed to said base, and shoe supporting means including a heel post vertically movable with respect to said bow member, a cam pinned to said post and having a plurality of faces adapted selectively to abut said bow member to limit upward movement of said post, and means holding said post against downward movement.

7. A shoe press comprising a base member having an inflatable pad, a rigid bow member affixed

to said base, and shoe supporting means including a hollow housing associated with said bow member, a heel post and an associated cam vertically insertable in said housing with said cam in abutment with the top of the housing, said cam being selectively locatable in any of a plurality of positions to determine the height of said post with respect to said bow member, and retaining means for holding said post against downward movement.

8. A shoe press comprising a base member having an inflatable pad, a rigid bow member integrally carried by said base member, a toe post integrally carried by said bow member, a heel post slidably carried by said bow member, and means including a cam interposed between said bow member and heel post for varying the height of the latter.

WILLIAM C. CARD, JR.
